United States Patent Office

Des. 178,258
Patented July 10, 1956

178,258

MILK BOTTLE

James I. North, Baltimore, Md.

Application August 5, 1955, Serial No. 37,333

Term of patent 14 years

(Cl. D58—6)

Fig. 1.

*Fig. 3.**Fig. 4.**Fig. 5.**Fig. 2.*

Fig. 1 is a perspective view of a milk bottle showing my new design;

Fig. 2 is a side elevational view thereof taken on a reduced scale;

Fig. 3 is a top plan view thereof;

Fig. 4 is a bottom plan view thereof;

Fig. 5 is a cross-sectional view thereof, taken on the line 5—5 of Fig. 2.

What is claimed is:

The ornamental design for a milk bottle, as shown.
